UNITED STATES PATENT OFFICE

2,448,019

GRINDING APPARATUS

John C. Curtis, Claremont, N. H., assignor to Joy Manufacturing Company, a corporation of Pennsylvania

Application December 30, 1942, Serial No. 470,688

9 Claims. (Cl. 51—95)

1

This invention relates to grinding apparatus, and more particularly, but not exclusively, to improved apparatus for grinding detachable rock drill bits in order to determine the proper bit gauge.

Many rock drill bits are of the so-called double-taper type, having the rearward portions of their bodies bounded by a frusto-conical surface the elements of which make an angle of about 14° with the axis of the bit; and the forward portions of these bits have their lateral surfaces also in coincidence with frusto-conical surfaces, these latter frusto-conical surfaces having their elements at an angle of about 5° with the bit axis. The latter portions of these bits determine the gauge. During the bit grinding operation, in certain known forms of grinding apparatus, the drill bit was usually rapidly rotated about its axis as it was moved toward and from the grinding wheel periphery, while maintained with its axis of rotation substantially at an angle of 5° to the axis of rotation of the grinding wheel. By contacting the drill bit with the grinding wheel in such a manner, it was found that wheel wear was excessive and uneven, so that frequent dressing of the wheel was necessary. This resulted in decreased life of the wheel and increased cost of grinding.

It is an object of the present invention to provide an improved bit grinding apparatus for overcoming the disadvantages of previously known apparatus. Another object is to provide an improved bit grinding apparatus in which the bit is guided for movement in a rectilinear path, tangential with respect to the grinding wheel periphery, so that the grinding wheel is evenly worn away, substantially reducing the necessity of dressing the wheel. A further object is to provide improved means for supporting and guiding a drill bit during its movement with respect to the grinding wheel. Yet another object is to provide improved means for rapidly rotating the drill bit as it is moved in a rectilinear path tangentially with respect to the grinding wheel. A still further object is to provide improved means for supporting the drill bit for adjustment into different angularly related positions with respect to the grinding wheel. Still another object is to provide an improved bit grinding apparatus embodying means for effecting feeding movement of the drill bit in a rectilinear path tangentially with respect to the grinding wheel. Yet another object is to provide improved supporting and guiding means for the drill bit for guiding the latter in a rectilinear path tangentially with

2

respect to the grinding wheel while the axis of the drill bit is maintained at right angles to the axis of rotation of the grinding wheel. These and other objects and advantages of the invention will, however, hereinafter more fully appear.

In the accompanying drawings there is shown for purposes of illustration one form which the invention may assume in practice.

In these drawings:

10 Fig. 1 is a plan view of a bit grinding apparatus constructed in accordance with an illustrative embodiment of the invention.

Fig. 2 is an elevational view, partially shown in section, of the grinding apparatus shown in 15 Fig. 1.

Fig. 3 is a view partially in vertical section and partially in elevation showing a drill bit in operative position on the work holder shaft.

Fig. 4 is a vertical sectional view taken substantially on line 4—4 of Fig. 1.

Fig. 5 is a vertical sectional view taken substantially on line 5—5 of Fig. 1.

Fig. 6 is an enlarged detail sectional view taken substantially on line 6—6 of Fig. 2.

25 Fig. 7 is an enlarged detail sectional view taken substantially on line 7—7 of Fig. 4, with parts in plan.

Fig. 8 is a view similar to Fig. 4, with parts shown in full and with the work holder in an 30 inclined position.

Fig. 9 is a fragmentary view similar to Fig. 2, showing the work holder in its raised position with respect to the grinding wheel.

Fig. 10 is an enlarged detail sectional view 35 taken substantially on line 10—10 of Fig. 2.

Fig. 11 is a somewhat schematic view, showing drill bits of different diameters in grinding relation with the grinding wheel.

In this illustrative embodiment of the invention there is shown a conventional grinding wheel 1, and improved supporting and guiding means, generally designated 2, for a work piece 3.

The work piece 3 is herein in the form of a 40 detachable rock drill bit which may be of a type similar to that shown in the patent to one Paul H. Nast, No. 2,168,102, patented August 1, 1939. As illustrated, the drill bit comprises a body 4 provided with a threaded socket 5 and adapted for attachment to the threaded end of

45 a conventional drill rod or steel in the manner well known to those skilled in the art. The bit body has pairs of wings 6, 6 and 7, 7, the former having aligned cutting edges 8 lying in a diametric line and the latter having arcuate chopping edges 50 9 lying at the outer periphery of the bit. The

55

drill bit shown is of the so-called double-taper type, and the wing peripheries are bounded by a forward, slightly tapered, frusto-conical surface 11 and a more sharply tapered, rearward, frusto-conical surface 12. The forward conical surface 11 is usually such that its elements make an angle of substantially 5° with the bit axis while the rearward surface 12 is usually such that its elements make an angle of substantially 14° with the bit axis, although it will be understood that these degrees of taper may vary considerably in different size bits. It is to the grinding of the forward, frusto-conical surface 11, in order to determine the proper bit gauge, that the present invention relates.

The improved grinding apparatus comprises a bed frame or base 14 on which is carried a motor 15, to the power shaft of which the grinding wheel 1 is secured, so that the motor may rapidly rotate the grinding wheel. There are parallel horizontal guides 16 attached to the end portions of a bracket 17 secured to the bed frame, and a horizontal frame 18 is slidably guided on these parallel guides. Carried by the sliding frame 18 are substantially vertical guides 19 rigidly connected at their upper ends by a cross plate 20. The guides 16 and 19 comprise tie-bolts passing through spacing sleeves, and the ends of the sleeves may be seated in appropriately spaced bores in the parts by which they are supported, in order to maintain the guides in proper spaced relation. A crosshead 21 is slidably guided for vertical movement along the vertical guides. A hand lever 22 is pivoted at 23 on the bed frame and is pivotally connected at 24 as by a pin and slot to a lug 25 integral with the frame 18, for sliding the latter back and forth along the horizontal guides. For moving the crosshead 21 along the vertical guides there is provided a chain sprocket 26 arranged between the guides and fixed to a horizontal shaft 27 journaled in suitable openings in the vertical guides near their lower ends, and fixed to the shaft 27 is a hand wheel 28. The sprocket 26 engages a chain 29 which is guided at its upper portion by a guide sprocket 30 fixed to a horizontal shaft 31, suitably journaled in openings in the vertical guides near their upper ends. This chain is attached at its ends at 32 to the crosshead, so that when the sprocket 26 is rotated by the hand wheel, the chain is circulated relative to its guides to move the crosshead either upwardly or downwardly along the vertical guides. Attached at one end at 33 to the crosshead is a chain 34 which passes around a guide sprocket 35 suitably journaled on the shaft 31. The chain 34 also passes around a guide sprocket 36 journaled on a horizontal shaft 37 at the upper end of a standard 38 mounted on the bed frame. The other end of the chain 34 is attached at 39 to a counterweight 40 which, to a large extent, counterbalances the weight to the crosshead so that manual feeding of the latter, together with the parts supported thereby, upwardly along the guides is facilitated. A suitable stop 41 is provided for limiting downward movement of the crosshead along the vertical guides.

In accordance with this invention, swiveled at 42 on a horizontal axis on a vertical plate 43 secured to the crosshead 21, is a vertical work supporting plate 44. Screws 45 secured to the plate 43 and passing through arcuate slots in the swivel plate 44, limit the extent of swinging movement of the swivel plate. By tightening these screws the swivel plate may be firmly

secured in adjusted position. Projecting laterally from the swivel plate is a substantially horizontal arm 46 which carries a support 47 for a motor 48. Fixed to the upright motor power shaft is a spur pinion 49 meshing with a spur gear 50 journaled on a vertical shaft 51 mounted on the support 47. Also journaled on the shaft 51 and secured to the gear is a pulley 52 connected by an endless drive belt 53 to a pulley 54 connectible to an upright work holder shaft 55. The shaft 51 passes through an arcuate slot 56 on the support 46 (Fig. 7), and the lower end of the shaft is threaded to receive a tightening nut 57. When the nut 57 is loosened the shaft 51 may be 15 moved in the arcuate slot 56, moving the pulley 52 horizontally about an axis coincident with the axis of the power shaft of the motor 48, thereby to vary the tension of the drive belt 53 in an obvious manner. When the drive belt is properly 20 tensioned, the nut 57 may be tightened to hold securely the parts in adjusted position. The work holder shaft 55 extends through a bore 58 of a barrel 59 integral with the swivel plate 44, and the shaft 55 is suitably journaled in bearings 25 supported within the barrel. The pulley 54 is connectible to the shaft 55 by means of a friction clutch 60 including a cone clutch element 61 fixed to the shaft and a cooperating clutch 62 integral with the pulley. A coil spring 63 surrounds the shaft 55 between the upper head of the barrel 59 and the lower surface of the pulley for urging the clutch elements yieldingly into frictional engagement. Other known types of friction clutches may be used in place of that shown, if 30 desired.

In this instance, journaled on a depending bracket 64 carried by the cross plate 20 at the upper ends of the vertical guides is a roller 65, and when the crosshead 21 is fed upwardly along 40 the vertical guides the upper surface of the pulley 54 engages the roller and moves into the position shown in Fig. 9 to release the upper clutch element 61 from the clutch element 62 to effect interruption of the drive between the motor and 45 work holder shaft. Thus it will be seen that when the work holder reaches its limit of travel along the vertical guides, the drive of the holder shaft is automatically interrupted. When the crosshead 21 is again lowered, the clutch is automatically applied by the coil spring. As previously mentioned, by loosening the screws 45 and adjusting the swivel plate 44 on its swivel axis, the angular relation of the work holder with respect to the grinding wheel may be varied. The 50 release roller 65 is so arranged that in all normal positions of adjustment of the swivel plate 44 on its swivel axis, the clutch is released when the work holder reaches its limit of upward travel.

As shown in Fig. 3, the work holder shaft 55 55 is threaded at 66 at its lower end, and the detachable drill bit 3 is adapted to be threaded onto the shaft with the threaded socket 5 of the bit receiving the threaded end of the shaft. It will be evident that the bit may be attached to the work holder shaft in various manners and that drill bits of different diameters, as indicated at A and B in Fig. 11, may be attached to the shaft.

The mode of operation of the improved grinding apparatus will be clearly apparent from the description given. Upon starting of the motor 15 the grinding wheel 1 is rapidly rotated. The angular position of the work piece with respect to the periphery of the grinding wheel may be adjusted simply by loosening the screws 45 and 70 swivelling the plate 44 into the desired relation.

The work holder may be swung from the vertical position shown in Fig. 4 with the axis of the work holder shaft perpendicular to the axis of rotation of the grinding wheel, to the inclined position shown in Fig. 8 with the holder shaft axis inclined slightly (herein at an angle of 5°) with respect to the vertical. The screws 45 may thereafter be tightened to clamp the parts firmly in position. It will be understood prior to the grinding operation that the work holder may be in its raised position and, if desired, the work holder may be in the position shown in Fig. 9 with the friction clutch held released by the roller 65 with the pulley 54. The bit may then be attached to the work holder shaft. The motor 48 may then be started and upon lowering of the work holder along the vertical guides, the friction clutch is automatically applied by the coil spring, thereby connecting the work holder to the shaft of the motor so that the drill bit is rapidly rotated. The operator may then grasp the lever 22 to manipulate the latter, thereby to move the work holder laterally along the horizontal guides to bring the drill bit into operative relation with the grinding wheel. As the drill bit is rapidly rotated with the work holder shaft, the operator may manipulate the hand wheel 28 to effect, through the chain and sprocket connections 26, 29, 30, movement of the drill bit in a rectilinear path tangentially with respect to the grinding wheel periphery, thereby properly to grind the slightly inclined forward tapered surface 11 of the drill bit to determine the proper bit gauge. The counterweight 40 facilitates raising of the work holder and crosshead vertically along the vertical guides.

The pulley 52 may be adjusted relative to the motor shaft simply by loosening the nut 57 and swinging the pulley about the motor shaft axis, thereby to vary the tension of the driving belt. When the work holder is in its raised position; that is, when it reaches its limit of vertical travel along the vertical guides, the roller 65 engaging the upper surface of the pulley 54 holds the clutch member 62 out of engagement with the clutch member 61 so that drive of the work holder shaft is interrupted.

As the periphery of the grinding wheel engages the work during the grinding operation, it evenly wears away, and by moving the work piece in a rectilinear path tangentially with respect to the wheel periphery, the wheel wear is evenly distributed over the wheel periphery between the side surfaces of the wheel. For instance, after grinding small diameter bits, as indicated at A in Fig. 11, larger diameter bits B may be placed against the wheel so the wheel periphery which was worn sharply concaved, is worn away at the sides. By grinding different size drill bits, the wheel wear is therefore evenly distributed over the face of the wheel so that the need of special dressing tools for the wheel is eliminated. This greatly increases the effective life of the wheel and decreases the grinding cost.

Instead of the hand lever 22 and the hand wheel 28, power devices may be employed to effect the movements of the work with respect to the grinding wheel in an obvious manner. Under certain conditions the counterweight 40 and its associated chain and sprocket connections 34, 35, 38 may be omitted, thus eliminating the need of the standard 38. Such counterweight would obviously be unnecessary if a power feed is provided in lieu of the hand wheel. Under some circumstances, a cylindric surface may be ground

on a work piece, instead of the frusto-conical surface disclosed, and at that time, the work holder would be adjusted into its vertical position shown in Fig. 4. Also work pieces other than drill bits may be ground by the improved apparatus. Other modes of operation and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a grinding apparatus, a grinding wheel, means providing rectangularly related guideways, said guideways lying in planes perpendicular to planes including the axis of rotation of said wheel, a rotatable work holder mounted on said guideway-providing-means for movement along said guideways and carrying a workpiece, means for driving said work holder to rotate the workpiece about its longitudinal axis during the grinding operation, means for moving said work holder along one of said guideways to move the workpiece in generally the direction of its axis along a rectilinear path tangentially with respect to the wheel periphery, means for swivelling said work holder on an axis parallel to the axis of rotation of said wheel to incline the longitudinal axis of the workpiece with respect to its rectilinear path, and means for moving said work holder along the other guideway to move the workpiece in a direction at substantially right angles to its longitudinal axis toward and from the wheel periphery.
2. In a grinding apparatus, a base, a grinding wheel, a horizontal guideway on said base, a support movable along said guideway, a second guideway carried by said movable support and arranged at right angles to said first guideway, a second support movable along said second guideway, a member swivelled on said second support on an axis disposed at right angles to said second guideway and parallel to the axis of rotation of said grinding wheel, a rotatable work holder journaled on said swivelled member and carrying a workpiece, means for rotating said holder to effect rotation of the workpiece about its longitudinal axis, means for moving said second support along its guideway to move the workpiece along a rectilinear path tangentially relative to the wheel periphery, said member being turnable on its swivel to incline the longitudinal axis of the workpiece with respect to its rectilinear path, and means for moving said first support along its guideway to move the workpiece substantially in a radial direction with respect to the wheel toward and from the wheel periphery.
3. In a grinding apparatus, a base, a grinding wheel, a horizontal guideway on said base, a support movable along said guideway, a second guideway carried by said movable support and arranged at right angles to said first guideway, a second support movable along said second guideway, a rotatable work holder journaled on said second support and carrying a workpiece, means for driving said holder to effect rotation of the workpiece about its longitudinal axis, means for moving said second support along its guideway.

to move the workpiece along a rectilinear path tangentially relative to the wheel periphery, means for moving said first support along its guideway to move the workpiece substantially in a radial direction with respect to the wheel toward and from the wheel periphery, said holder driving means including motor driven connections carried by said second support, and releasable clutch means movable rectilinearly with the workpiece for automatically interrupting the drive of said work holder when the workpiece is in its retracted position.

4. In a grinding apparatus, a base, a grinding wheel, a horizontal guideway on said base, a support movable along said guideway, a second guideway carried by said movable support and arranged at right angles to said first guideway, a second support movable along said second guideway, a member swivelled on said second support on an axis disposed at right angles to said second guideway, a rotatable work holder journaled on said swivelled member and carrying a workpiece, means for driving said holder to effect rotation of the workpiece about its longitudinal axis, means for moving said second support along its guideway to move the workpiece along a rectilinear path tangentially relative to the wheel periphery, said member being turnable on its swivel to incline the longitudinal axis of the workpiece with respect to its rectilinear path, means for moving said first support along its guideway to move the workpiece substantially in a radial direction with respect to the wheel toward and from the wheel periphery, said holder driving means including motor driven connections carried by said swivelled member, and releasable clutch means movable rectilinearly with said work holder for automatically interrupting rotation of the workpiece when said work holder is in its retracted position and irrespective of the swivelled position of said work holder.

5. In a grinding apparatus, a grinding wheel, a rotatable work holder carrying a workpiece, means for driving said work holder to rotate the workpiece about its longitudinal axis during the grinding operation, means for moving said work holder to move the workpiece generally in the direction of its axis along a rectilinear path tangentially to the wheel periphery, means for swivelling said work holder on an axis parallel to the axis of wheel rotation to incline the longitudinal axis of the workpiece with respect to its rectilinear path and for maintaining said work holder in its swivelled position during aforesaid rectilinear movement of the workpiece, and means engageable by said work holder and effective irrespective of the swivelled position of said work holder for automatically interrupting drive of the latter when the workpiece reaches its limit of travel in one direction along aforesaid rectilinear path.

6. In a grinding apparatus, a grinding wheel, a rotatable work holder carrying a workpiece, means for driving said work holder to rotate the workpiece about its longitudinal axis during the grinding operation, means for moving said work holder to move the workpiece generally in the direction of its axis along a rectilinear path tangentially to the wheel periphery, said driving means for said work holder including a clutch movable translationally with said work holder during aforesaid movement of said workpiece and through which said work holder is driven, and means comprising an abutment which remains stationary during aforesaid movement of said

work holder and with which an element of said clutch is engageable for automatically effecting release of said clutch to interrupt rotation of said work holder when the workpiece reaches its limit of travel in one direction along aforesaid rectilinear path.

7. In a grinding apparatus, a base, a grinding wheel, a horizontal guideway on said base, a support movable along said guideway, a second guideway carried by said movable support and arranged at right angles to said first guideway, a second support movable along said second guideway, a member swivelled on said second support on an axis disposed at right angles to said second guideway and parallel to the axis of rotation of said grinding wheel, a rotatable work holder journaled on said swivelled member and carrying a workpiece, means for driving said holder to effect rotation of the workpiece about its longitudinal axis, means for moving said second support along its guideway to move the workpiece along a rectilinear path tangentially relative to the wheel periphery, said member being turnable on its swivel to incline the longitudinal axis of the workpiece with respect to its rectilinear path, means for moving said first support along its guideway to move the workpiece substantially in a radial direction with respect to the wheel toward and from the wheel periphery, said holder driving means including motor driven connections carried by said swivelled member, and means movable rectilinearly with said work holder for automatically interrupting rotation of the workpiece when said work holder is in its retracted position.

8. In a grinding apparatus, a grinding wheel, a rotatable work holder carrying a workpiece, means for driving said work holder to rotate the workpiece about its longitudinal axis during the grinding operation, means for moving said work holder to move the workpiece along a rectilinear path tangentially of the wheel periphery, means for swivelling said work holder on an axis parallel to the axis of rotation of said wheel to incline the longitudinal axis of the workpiece with respect to its rectilinear path, means for moving said work holder to move the workpiece in a direction at substantially right angles to its longitudinal axis toward and from the wheel periphery, and means for automatically interrupting drive of said work holder when the workpiece is in retracted position, said interrupting means being effective to interrupt drive of said work holder irrespective of the swivelled position of said work holder.

9. In a grinding apparatus, a grinding wheel, a rotatable work holder carrying a workpiece, means for driving said work holder to rotate the workpiece about its longitudinal axis during the grinding operation, means for moving said work holder to move the workpiece generally in the direction of its axis along a rectilinear path tangentially of the wheel periphery, means for swivelling said work holder on an axis parallel to the axis of rotation of said wheel to incline the longitudinal axis of the workpiece with respect to its rectilinear path, means for moving said work holder to move the workpiece in a direction at substantially right angles to its longitudinal axis toward and from the wheel periphery, and means including a clutch movable translationally with said work holder and a relatively stationary stop with which an element of said clutch is engageable for automatically interrupting drive of said work holder when the workpiece is in retracted

9

position, said clutch being engageable with said stop irrespective of the swivelled position of said work holder.
